WILLIAM A. STOFER, OF FOXBURG, PENNSYLVANIA.

CAR-BRAKE.

SPECIFICATION forming part of Letters Patent No. 395,012, dated December 25, 1888.

Application filed September 24, 1888. Serial No. 286,165. (No model.)

To all whom it may concern:

Be it known that I, WILLIAM A. STOFER, of Foxburg, in the county of Clarion, State of Pennsylvania, have invented a certain new 5 and useful Improvement in Car-Brakes, of which the following is a description sufficiently full, clear, and exact to enable any person skilled in the art or science to which said invention appertains to make and use 10 the same, reference being had to the accompanying drawings, forming part of this specification, in which—

Figure 1 is a bottom plan view of a portion of a railway-train provided with my improved brake; Fig. 2, a perspective view of one of the car-trucks detached and enlarged; Fig. 3, an elevation of one of the brake-shoes and rod detached; Fig. 4, an enlarged bottom plan view of a portion of a car provided with 15 my improvement; Fig. 5, a side elevation of the same; Fig. 6, a vertical section of a portion of an engine-cab, showing the means for operating the brake; and Fig. 7, an enlarged elevation of the crank and gears detached 20 from the cab.

Like letters and figures of reference indicate corresponding parts in the different figures of the drawings.

My invention relates to that class of brakes 30 which are particularly adapted for use on freight-cars and are operated from the engine or any one of the cars; and it consists in certain novel features, as hereinafter fully set forth and claimed, the object being to produce a simpler, cheaper, and more effective device of this character than is now in ordinary use.

The nature and operation of the improvement will be readily understood by all conversant with such matters from the following 40 explanation.

In the drawings, A B represent the cars; C, the locomotive-cab; D E, the car-wheels, and H H² the brake-shoes, these parts being all 45 of the ordinary form and construction, excepting as hereinafter specified.

A longitudinally-arranged rod, J, connects the brake-shoes H H² on the same side of the car and keeps them in their proper positions, 50 said rod being capable of adjustment by means of the shorter threaded portion, K, of the same. An equalizing-bar, L, is pivoted

centrally at a to the body of each car, and to the outer ends of said bar longitudinally-arranged connecting-rods M N are pivoted 55 at b.

A diagonally-arranged rod, P, provided with a stiff coiled spring, d, at one end, for the purpose of relieving any strain on the several parts, is pivoted at t to the bar L, the opposite end of said rod being secured centrally to a horizontally-arranged bar, g, secured by vertical arms f to a rock-bar, R, on each truck Q of the car.

The rock-bar R is pivoted on plates O, secured to the frame-work S of the car-truck Q, and is provided with outwardly-projecting short lugs h, to which are attached at their upper ends lever-arms i, the lower ends of said lever-arms being pivoted to two of the 70 brake-shoes H. The rear brake-shoes, H², are supported by means of arms j, pivoted at their upper ends to the plates O on the rear side of the car-truck opposite to that on which hangs the rock-bar R. The horizontal bar g of the 75 rock-bar R is provided with a coiled spring, k, the purpose of which is to keep the parts in their normal position when not in use or when the shoes H H² are released from pressure 80 against the wheels E D.

The longitudinally-arranged connecting-rods M N are pivoted to the ends of the equalizing-bar L and provided with hooks n and chains p at their ends, by which the bars on adjacent cars of the train are connected. 85 Each car is provided with the usual hand-wheels, q, (see Fig. 1,) which are attached to the rods M N by means of short links r.

It will be readily seen that by turning the hand-wheels q in the usual manner the rods 90 N will be moved in the direction of arrows 2 and the rods M in the direction of arrows 3 in Fig. 1, thereby causing the equalizing-bar L to turn on its pivot a and draw forward the rod P, thereby drawing outward the bar g of 95 the rock-bar R. This movement of the rock-bar draws the lever-arms i upward and forces the brake-shoes H against the wheels D. At the same time the shoes H², being connected with the shoes H by the rod J, are forced into 100 engagement with their wheels E as said shoes are drawn upward.

The operation of the brake upon only one, or the rear, set of wheels is illustrated; but it

will be understood that the opposite rod, P, pivoted to the opposite end of the bar L, acts at the same time and in the same manner upon the wheels of the forward truck.

5 It will be clearly seen that when the hand-wheels *q* are actuated great power is obtained over the brakes H, because of the long leverage of the arms *f* and the short leverage of the lugs *h* on the rock-bar.

10 Occasion often arises for the application of the brakes throughout the train from the engine. For this purpose I have provided a system of mechanism (shown in Figs. 6 and 7) by means of which the engineer or fireman 15 can bring the train to a full stop at once. A frame, T, is firmly bolted to the cab C of the locomotive, and upon this are journaled in suitable bearings shafts *s m*. A chain, *v*, is secured at one end to the end of a bar, M, 20 and passes over a friction-pulley, 60, secured to the cab, and upward through the floor 65 thereof and around the shaft *m*. One end of said shaft *m* is journaled in a block, 20, and mounted thereon is a pinion, *w*, which 25 meshes with the gear-wheel W on the shaft *s*. The block 20 is movable laterally by means of the releasing-lever 25. A pawl, 12, is pivoted on the gear-wheel W and engages a ratchet-wheel, 10, which is actuated by a 30 lever-arm, 14, pivoted to the frame. Every movement of the lever-arm 14 in the direction of arrow 4 causes the gear-wheel W to move in the same direction and the pinion *w* to travel in the opposite direction, thus winding up the chain V on the shaft *m*, drawing forward the rod M, and operating the brakes, 35 as described.

The frame T is provided at its upper end with a retaining-pawl, 15, (see Fig. 7,) which 40 engages the gear W, the purpose of said pawl being to hold said gear during the forward stroke of the lever 14. To release the brakes from the engine, the lever 25 is drawn forward into the position shown by the dotted lines in 45 Fig. 7, thus disengaging the pinion *w* from the gear W, when the tension on the chain *v* will cause it to unwind from the shaft *m* and release the brakes.

Having thus explained my invention, what 50 I claim is—

1. In a device of the character described, the combination of a car, an equalizing-bar centrally pivoted to said car, longitudinally-arranged connecting-rods pivoted to said bar, 55 rock-bars secured to the car-trucks, actuating-rods connecting said equalizing-bar and rock-bar, and levers pivoted to said rock-bars and the brake-shoes of the car, whereby said shoes may be forced into engagement with the car-wheels as said equalizing-bar is actuated by the connecting-rods, substantially as set forth.

2. In a device of the character described, the combination of a car, rock-bars pivoted 65 to the truck of said car, levers pivoted to said rock-bars and the brake-shoes of said truck,

an adjustable rod connecting the shoes of opposite wheels, an equalizing-bar pivoted to said car, and an actuating-rod provided with a spring and connecting said rock-bar with 70 said equalizing-bar, whereby the brake-shoes may be lifted into engagement with the wheels as said equalizing-bar is moved, substantially as specified.

3. In a device of the character described, 75 the combination of a car provided with trucks and a brake-wheel, rock-bars hinged to said trucks, brake-shoes connected by pivoted lever-arms with said rock-bars, adjustable rods connecting opposite brake-shoes, an equalizing-bar pivoted centrally to said car, actuating-rods pivoted to said bar and rock-bars, and connecting-rods pivoted to said equalizing-bar and connected with said brake-wheel, whereby 80 said shoes are lifted into engagement with the car-wheels as said brake-wheels are operated, 85 substantially as set forth.

4. In a device of the character described, the combination of a car provided with trucks, 90 rock-bars hinged to said trucks, brake-shoes connected by pivoted lever-arms with said rock-bars, adjustable rods connecting opposite brake-shoes, an equalizing-bar pivoted centrally to said car, actuating-rods pivoted to 95 said bar and rock-bars, longitudinally-arranged connecting-rods pivoted to said equalizing-bar, an engine, and a chain connecting said connecting-rods with a ratchet mechanism in said engine, whereby said chain may be wound and the brake-shoes lifted into engagement with the wheels, substantially as 100 specified.

5. In a device of the character described, the car A, provided with the trucks Q and 105 wheels E D, in combination with the rock-bars R on said trucks, the brake-shoes H H², the pivoted levers *i j*, connecting said shoes and truck, the adjustable rod J, connecting said shoes, the bar L, pivoted to said car, the rod P, provided with the spring *d* and connecting 110 the bar L and rock-bar R, and adjunctive mechanism for actuating said bar L, substantially as set forth.

6. The car A, provided with trucks Q, wheels E, and brake-wheels *q*, the equalizing-bar L, 115 pivoted to said car, the rods M N, pivoted to said bar and connected by chains *p* with said brake-wheels, the rock-bars R on said trucks, the rod P, connecting the bar L with said rock-bars, the brake-shoes H H², connected by 120 the rod J, the pivoted levers *i*, connecting the shoes H with said rock-bar, and the levers *j*, connecting the shoes H² with said truck, all being constructed, combined, and arranged to operate substantially as specified.

7. The cab C, provided with the frame T, the shafts *m s*, journaled in said frame, the movable block 20, and lever 25, for actuating the same, the gear W on the shaft *s*, the pinion *w* on the shaft *m*, the ratchet 10, the pawl 12 on the gear W, engaging said ratchet, the lever 14 on the shaft S, and the chain *v*, con-

necting the shaft *m* with the brakes of the cars, all being constructed, combined, and arranged to operate substantially as set forth.

8. In a device of the character described, 5 the equalizing-bar *L*, pivoted to the car, connecting-rods *M N*, pivoted to said bar, the rock-bars *R*, pivoted to the car-truck and provided with the arms *f* and bar *g*, levers connecting said rock-bars with the brake-shoes,

and the actuating-rod *P*, connecting the equalizing-bar with the bar *g*, whereby said brake-shoes may be lifted into engagement with the wheels when said connecting-bars are moved, substantially as specified.
